(57) **CLAIM**

The ornamental design for an upper for an article of footwear, as shown and described.

DESCRIPTION

FIG. 1 is a lateral side view in perspective of an upper for an article of footwear showing our new design;

FIG. 2 is a lateral side view thereof;

FIG. 3 is a medial side view thereof;

FIG. 4 is a top view thereof;

FIG. 5 is a bottom view thereof;

FIG. 6 is a front view thereof;

FIG. 7 is a rear view thereof; and,

FIG. 8 is a lateral side view in perspective of the upper for an article of footwear of FIG. 1 showing environmental structure (lacing) incorporated with the upper.

The upper for an article of footwear illustrated in the drawings is a first embodiment having a right-footed form of the upper for an article of footwear. A second embodiment, which is for the left-footed form of the upper for an article of footwear is a mirror image of the right-footed form, is not illustrated and is also claimed. The dashed broken lines in the figures, showing portions of the upper for an article of footwear and the sole environment, form no part of the claimed design.
